UNITED STATES PATENT OFFICE.

MICHIEL J. ULINE AND WILLIAM B. HILL, JR., OF TOLEDO, OHIO; SAID ULINE AS SIGNOR TO THE ULINE ICE-SCORING MACHINE COMPANY, OF WILMINGTON, DELAWARE, A CORPORATION OF DELAWARE.

MACHINE FOR SCORING ICE.

Application filed April 21, 1922. Serial No. 555,824.

To all whom it may concern:

Be it known that we, MICHIEL J. ULINE and WILLIAM B. HILL, Jr., citizens of the United States, residing at Toledo, in the county of Lucas and State of Ohio, have invented a certain new and useful Improvement in Machines for Scoring Ice, of which the following is a full, clear, and exact description, reference being had to the accompanying drawings.

This invention relates to a method of and machine for scoring or grooving blocks of ice preparatory to breaking them into pieces of given size. The purpose of such treatment is to facilitate the cutting of the ice into pieces of predetermined weight at the time of delivery to the consumer, the scores or grooves defining portions of the minimum weight sold, and obviously larger pieces of certain weight may be cut by including within them an appropriate number of such portions.

The objects of the invention are to provide a novel method by which ice may be scored by applying heat directly thereto along defined lines and in a particularly convenient, expeditious, and economical manner; to provide a machine through which this method may be practiced; to provide a machine of the immediately foregoing nature which is so designed and constructed as to operate efficiently at the minimum expenditure of heat; to provide an ice scoring machine wherein steam is employed as the heating medium for scoring the ice and wherein the draining of the condensate is so provided for as to make it unnecessary to shut off the steam between successive operations; and to provide an ice scoring machine wherein steam at a comparatively low pressure may be used effectually for scoring the ice.

Other objects are to provide a scoring machine through which the ice may move in a constant direction, in contradistinction to those ice scoring machines wherein the ice enters the machine in one direction, is moved therein in another direction, and may be discharged therefrom in still another direction; to provide a machine of the aforesaid character which is very convenient of use and which greatly expedites the scoring operation; to provide in such a machine a stop for positioning the block of

ice in proper relation to the scoring means, and which stop may be conveniently released by the operator after the ice has been scored; to provide an ice scoring machine wherein the scoring elements are readily adjustable to the end that accuracy may be obtained in the weight of the parts into which the block is to be divided; and to provide an ice scoring machine wherein steam pipes or the like constitute the scoring elements and which, through being adjustable for the aforesaid purpose, possess no joints which are disturbed or likely to be loosened through such an adjustment.

The foregoing objects, with others hereinafter appearing, are attained in the embodiment of our invention illustrated in the drawings accompanying and forming a part hereof and wherein Fig. 1 is a side elevation of the machine; Fig. 2 is a perspective view of a block of ice showing, in dotted lines thereon, the position and arrangement of the scores or grooves produced by the machine; Fig. 3 is a plan view of the machine; Fig. 4 is a face view of one of the side plates which carry the scoring blades; Fig. 5 is an elevational view of the inlet end of the machine; Fig. 6 is a vertical section through one of the side plates; Fig. 7 is an enlarged sectional detail on the line 7-7 of Fig. 6; and Fig. 8 is an enlarged fragmentary elevation of one of the corner posts, showing certain parts associated therewith.

The frame of the machine comprises a rectangular base plate 1, from each corner of which rises a post 2, and an X-shaped casting 3, having cross beams 4 at its ends, is applied to the tops of the posts. The posts 2 at each end of the machine are arranged in opposed relation to each other, and each incorporates a guideway 5 at its upper and at its lower end, and a recess 6 at its vertical center, the axes of the guideways and recess being parallel.

Extending between the corner posts on each side of the machine is a side plate 10 which has lugs 11 projecting from its four corners, said lugs being adapted to slide within the guideways 5 of the corner posts. Each side plate has applied to its outer face, adjacent its ends, bearings 12 within which a shaft 15 is journaled, the shafts on the two sides of the machine extending beyond

the ends of the side plates, through the recess 6 of the corner posts, and being equipped therebeyond with spur gears 16 that mesh with racks 18 that are shown as 5 incorporating brackets 19 by means of which they are attached to the corner posts. Handles 20 are applied to the shafts 15 adjacent the inlet end of the machine.

Plates 25 close the outer sides of the guide- 10 ways 5 and maintain the side plates 10 against shifting longitudinally by cooperation with the lugs 11. A rail 26 extends longitudinally of the base plate 1 at the transverse center thereof, and this rail consti- 15 tutes the support for the block of ice when the same is within the machine. As is well known to those familiar with the art, ice is manufactured in blocks which taper gradually from one end to the other so as to facilitate removal from the molds, and in order to support the block of ice with its central axis horizontal, the upper surface of the rail 26 is inclined gradually upwardly from the inlet toward the outlet end of the machine 20 at an angle corresponding to the taper of the adjacent face of the block. A stop 28 is movably sustained adjacent the outlet end of the machine and is pivoted, at its lower end, to one branch of a bell crank 29, 25 the other branch whereof is connected, through a rod 30, with the lever 31 of a foot pedal 32, said lever being pivoted intermediate its ends at 33 to a stationary structure 34. The pedal 32 is situated to one side of 30 the path of the ice, as will be seen by reference to Fig. 3. The stop 28 is normally held elevated by a spring 35 which surrounds the rod 30 and is compressed between the adjacent end of the bell crank 29 and a guide 36 10 through which the rod passes. It will be seen from this that when the foot pedal is depressed it will retract the stop 28 against the action of spring 35, the spring expanding to return the parts to their former positions upon releasing the pedal.

Extending the full length of each side plate 10, and situated on its inner face at the vertical center thereof is a blade 40 secured through its base flange 41 and screws 50 42 to the side plate. A steam pipe 45, of comparatively small diameter, extends the full length of the blade and is secured to its edge by any suitable means, the edge being preferably grooved to a depth substantially equal to the radius of the pipe so as to properly receive and support the pipe. T-slots 46 are shown as extending from end to end of each plate 10 in parallel relation to the blade 40, and connected to the plate by bolts 47 which have their heads engaged within the T-slots, are the base flanges 49 of vertically disposed blades 50, nuts 51 being applied to the outer ends of the bolts 47. 55 Steam pipes 52 are secured within the grooved edges 53 of the blades 50 in like

manner to that in which the pipe 45 is secured to the blade 40. This is illustrated in connection with one of the blades 50 in Fig. 7. The vertical blades 50 are arranged in pairs, the blades of the corresponding pairs 70 aligning with each other above and below the horizontal blade 40. The pipes 52 connect at their upper ends with an inlet manifold 55, which may be supplied with steam through a flexible hose 56, and at their lower ends 75 with a drain manifold 57 which may exhaust through a flexible hose 58. The inlet manifold 55 is shown as inclined upwardly from its middle, where it communicates with the supply hose 56, toward its ends for the obvious purpose of facilitating the flow of the steam; and for a similar reason the drain manifold 57 is reversely inclined from each end to where it joins the hose 58 at its middle. One end of the tube 45 connects with 80 the inlet manifold 55, and its other end has communicative connection with the adjacent end of the drain manifold.

To insure the block of ice being maintained upright on the rail 26, guides 60 may 90 be provided which are shown as formed by the downturned ends of plates 61 that are supported by the top casting 3.

In the use of the machine a block of ice is shoved small end foremost into the inlet 95 end of the machine until it is arrested by the stop 28. The operator then swings the handles 20 inwardly and downwardly imparting an inward movement to the side plates 10 by reason of the cooperation of the 100 gears 16 with the racks 18. The steam pipes 45 and 52, coming in contact with the ice, melt their way into the ice to a depth depending upon the distance of the inward travel of the side plates, thus instantly scoring the block longitudinally on each side at its vertical center, and vertically at properly spaced intervals lengthwise of the block so as to divide it into sections of given capacity. The handles 20 are then returned 110 to their normal position causing the gears 16 to travel outwardly along the racks 18 which results in the side plates being retracted, after which the operator may depress the 115 pedal 32 and retract the stop 28 thereby to release the ice so that it may be shoved on out through the discharge end of the machine.

The upper and lower ends of the pipes 52, 120 between the blades 50 and the manifolds 55 and 57, are of ample length to permit an appreciable lateral adjustment of the blades 50, the blade 40 having slots 40^b to allow sidewise movement of the pipes 52. This adjustment, it will be understood, is for the 125 purpose of obtaining accuracy of weight of the sections into which the block of ice is to be divided.

Considering the scoring blades 40 and 50, 130 attention is called to the fact that, in each

instance, it is the edge portion only of the blade—that is, the portion constituted of the pipe or tube—that performs the scoring operation inasmuch as this is the only portion that is heated, the blade proper remaining cool and serving purely as a support for the pipe. As a consequence, the heating fluid may be allowed to flow constantly, for regardless of this the cut will be made substantially no wider than the diameter of the pipe or the thickness of the blade. This would not be true if the entire blade were heated, for obviously as the edge portion would be melting its way into the ice, the heat radiated from the body portion of the blade would be melting the sides of the cut and enlarging it laterally, causing an unnecessary shrinkage of ice. To avoid this extra melting, the heating fluid would probably have to be shut off at about the instant the blade would be engaged with the ice.

Except where so limited by the terms of the appended claims or the state of the prior art, our invention is not restricted to the use of steam as the heating medium, as obviously other heated fluid may be circulated through the scoring pipes, or electrical heating elements may be substituted for the pipes, without departing from the spirit of our invention.

In the present well developed state of the electrical art, the immediately foregoing modification of the invention is so obvious that specific illustration is deemed unnecessary.

Having thus described our invention what we claim is:

1. In a machine of the character set forth, the combination of a support for a block of ice, a plate supported adjacent thereto for movement toward and from a block of ice sustained by said support, a scoring element carried by and spaced from the plate for engagement with the block of ice, means for heating the scoring element exclusively of the plate, and means for moving said plate as aforesaid.

2. In a machine of the character set forth, the combination of a support for a block of ice, a stop for positioning a block of ice on said support, carriers arranged on opposite sides of said support, scoring elements sustained by said carriers in spaced relation thereto and comprising conductors for a heating medium, means for moving the carriers inwardly to engage the scoring elements with the opposite sides of the block of ice, means for conveying a heating medium to the scoring elements, and means for retracting the aforesaid stop.

3. In a machine of the character set forth, the combination of a frame incorporating a support for a block of ice, side plates arranged on opposite sides of said support,

means for moving the side plates toward and from each other, ice scoring elements carried by the side plates in spaced relation thereto, and means for heating the scoring elements exclusively of the plates.

4. In a machine of the character set forth, the combination of a frame incorporating a support for a block of ice, side plates arranged on opposite sides of said support, a shaft rotatably supported by each side plate, gears carried by said shafts, racks supported by the frame wherewith the gears mesh, means for rotating the shafts thereby to move the side plates toward and from each other, and ice scoring elements carried by the side plates.

5. In a machine of the character set forth, the combination of a frame, a support for a block of ice incorporated therein, side plates arranged on opposite sides of the support, a shaft rotatably supported by each side plate, gears on the shafts, racks carried by the frame wherewith said gears mesh, means for rotating the shafts thereby to move the side plates toward and from each other, scoring elements carried by the side plates, said scoring elements constituting conductors for a heating medium, and means for conveying a heating medium to said conductors.

6. In a machine of the character set forth, the combination of a frame incorporating a support for a block of ice, a carrier sustained by the frame for movement toward and from a block of ice on the support, means for moving the carrier, scoring elements in the nature of conduits, members on the carrier, one for supporting each of said scoring elements in spaced relation to the carrier, an inlet manifold mounted on the carrier and wherewith said conduits communicate, and means for supplying a heating fluid to the manifold.

7. In a machine of the character set forth, the combination of a frame incorporating a support for a block of ice, carriers arranged on opposite sides of the support, mechanism for moving said carriers toward and from each other, scoring elements in the nature of conduits carried by the carriers in spaced relation thereto, inlet and outlet manifolds associated with each carrier and wherewith the conduits have communicative connection, and means for supplying a heating medium to the inlet manifolds.

8. In a machine of the character set forth, the combination of a frame incorporating a support for a block of ice, side plates arranged on opposite sides of the support, mechanism for moving the side plates toward and from each other, blades adjustably supported by the side plates, conduits applied to the edges of the blades, inlet and outlet manifolds associated with each of

the side plates and wherewith the conduits have communicative connection, and means for supplying a heating medium to the inlet manifolds.

5 9. In an ice scoring machine, a frame comprised of a base incorporating a support for a block of ice, posts rising from the base, there being two posts arranged in opposed relation to each other at points 10 spaced longitudinally of the base, said posts having guideways, side plates having extensions which are slideable within said guideways, means for moving the side plates toward and from each other, and ice 15 scoring elements carried by the side plates, said elements comprising conductors, and means for delivering a heating medium to said conductors.

10. In an ice scoring machine, a frame 20 comprised of a base incorporating a support for a block of ice, posts rising from the base, there being two posts arranged in opposed relation to each other at points spaced longitudinally of the base, said 25 posts having guideways, side plates having extensions which are slideable within said guideways, a shaft rotatably supported by each side plate, gears on said shafts, racks supported by the posts and wherewith the 30 gears mesh, means for rotating the shafts to move the side plates toward and from each other, and ice scoring elements carried by the side plates, said elements comprising conductors, and means for delivering 35 a heating medium to said conductors.

11. In a machine of the character set forth, the combination of a supporting structure incorporating a support for a block of ice, side plates slidably supported 40 by the structure on opposite sides of the support, means for moving the side plates toward and from each other, vertically disposed scoring elements carried by the side plates, said elements consisting of pipes, an 45 inlet manifold supported adjacent the upper edge of each side plate and wherewith the upper ends of the pipes have communicative connection, and an outlet manifold supported by each side plate adjacent its 50 lower edge and wherewith the lower ends of the pipes communicate.

12. In a machine of the character set forth, the combination of a support for a block of ice, a plate movable toward and

from a block of ice sustained by the support, means for so moving said plate, the plate having a series of substantially parallel T-slots or the equivalent thereof, a plurality of ice scoring elements having base flanges engaging the plate, and means 60 interlocking with the T-slots of the plate for securing the base flanges of the elements to the plate whereby the elements may be adjusted with respect to each other. 65

13. In a machine of the character set forth, the combination of a support for a block of ice, a member movable toward and from a block of ice on the support, means for so moving said member, an ice scoring element extending longitudinally of the 70 member, and a plurality of ice scoring elements arranged at substantially right angles to the former element above and below the same, and means attaching certain of the second mentioned elements to the member so that they may be adjusted in a direction longitudinally of the first mentioned element. 75

14. In a machine of the character set forth, the combination of a support for a 80 block of ice, a member movable toward and from a block of ice on said support, a plurality of scoring elements supported by the member and adjustable with respect thereto, an inlet manifold sustained in operative 85 relation to the member, the ice scoring elements including tubing which has communicative connection with the manifold, the tubing being flexible and of ample length to permit of an adjustment of the 90 elements with respect to the manifold, and means for moving the member as aforesaid. 95

15. In a machine of the character set forth, the combination of opposed plates 100 having ribs, means for heating the ribs exclusively of the plates, means for supporting a block of ice between the plates, and means for moving the plates inwardly thereby to engage the ribs with the ice and score it.

In testimony whereof, we hereunto affix our signatures.
